UNITED STATES PATENT OFFICE

WILLIAM R. MOORE, JR., OF HAGERSTOWN, MARYLAND, ASSIGNEE TO DECA DISC PHONOGRAPH COMPANY, OF WAYNESBORO, PENNSYLVANIA, A CORPORATION OF PENNSYLVANIA

SYNCHRONIZING TALKING MOTION PICTURE MACHINES

Application filed April 29, 1929. Serial No. 359,014.

This invention relates to mechanism for synchronizing talking motion picture machines, an object of the invention being to provide means for taking up all lost motion between the mechanism for playing the record and that for projecting the pictures so that the music and the pictures shall perfectly synchronize.

A further object is to provide improved driving connection between the motor and the several parts of the mechanism.

Further objects and advantages will become apparent as the description proceeds.

Referring to the accompanying drawings, which are made a part hereof and on which similar reference characters indicate similar parts,

Figure 1 is a view in elevation of my invention,

Figure 2 is a detail view showing one of the driving connections,

Figure 3, a detail view of the connection between the motor and the talking machine,

Figure 4, a detail view partly in section of the reducing gears between the motor and the record playing table, showing the means for adjusting the driving connections, and

Figure 5 is a section on line 5—5 of Fig. 1.

In the drawings, reference character 10 indicates a record table having a playing arm 11 and suitable transmitting elements 12 of well known electrical pick up type. The record table 10 is mounted on a shaft 13 and is driven by a motor 14 through shafts 15 and 16 and worm gear connection 17 and 18. The motor 14 is preferably an 1800 R. P. M. synchronous motor, and the worm gear drive is preferably a fifty-four to one reduction, whereby the record table is driven $33\frac{1}{3}$ revolutions per minute. In order to provide a flexible drive between the motor and the record table the shafts 15 and 16 are connected by means of a fibre strip 19. This strip has slots 20 and 21 through which pins 22 in the ends of the shafts 15 and 16 are positioned to connect the strip to the shafts. The slots permit a certain end play, and also provide a certain amount of torsional give in the fibre. This eliminates a considerable degree of the shock due to the rotation of the motor

and reduces vibration to a minimum. In synchronizing any two mechanisms it is necessary to take up all lost motion between the driving and driven parts. This is particularly necessary in machines for synchronizing talking machines and pictures. It is necessary therefore that the worm gear drive connections 17 and 18 must be as nearly absolutely correct as possible. In order to insure such close contact I have provided means for adjusting the worm and worm gear by means of set screws 24 and 25 which adjust the bearing in which the outer end of the shaft 16 rides toward or from the worm gear 18. The bearing is carried in a sleeve 26 having a depending lug 27 thereon against which the set screws 24 and 25 abut, these set screws being adjustably threaded through ears 29 on a housing 30, which housing forms the support for the record table and its driving elements. The sleeve 26 is pivoted at 31 to the frame or housing 30. The motor 14 is mounted upon a bracket or ledge 32 on the framework 33 which supports driving mechanism for the picture projecting elements. Shaft 34 on the motor is connected by means of flexible connections 35 with a shaft 36. Suitable reducing gearing similar to that shown at 17 and 18 is contained in a housing 37 by means of which sprocket wheel 38 is driven in a one to twenty ratio with respect to the motor 14—that is, the sprocket 38 is driven ninety revolutions per minute. A sprocket chain 39 passing over a sprocket 40 furnishes driving connection to the shaft 41 by means of which the picture projecting mechanism is driven. The sprocket wheel 40 is carried upon a post 42 which is secured to the bed of the machine and which is braced by means of posts 43. An idle pulley 44 is mounted on the support 43 this pulley being adjustable to provide suitable tension to the sprocket chain 39. Driving connection between the sprocket wheel 40 and the picture projecting mechanism is shown in detail in Fig. 2. This driving connection consists of a shaft 41 having a hub 46 secured on one end by means of a pin 47. The end of the shaft 41 is somewhat rounded to provide some freedom to the hub 46 to give it somewhat of a 100

swivel or universal joint action. The hub 46 is secured to the hub of the sprocket 40 by means of set screws 48. The other end of the shaft 41 has secured thereon a hub 49 having pins 50 axially positioned in its end for engagement with holes or between the spokes in a wheel on the projection mechanism drive, the said mechanism being driven by means of the pins 50. The shaft 41 has a key 51 which 10 engages keyways 52 in the shaft 41 the key 51 providing driving connection between the shaft and the collar 49. The key and the keyway in which it slides provide for axial movement of the hub 49 along the shaft 41. 15 A pin 53 is positioned in a hole in one side of the shaft 41 and is pressed outwardly by means of a spring 54 seated in the hole. The purpose of the pin 53 is to hold the collar 49 in operative position. The pin 53 may be 20 pressed in to permit the hub to be moved backward to disengage the pins 50 from driving connection with the means for driving the picture projecting mechanism, the pin 55 limiting the axial movement. When the hub 25 is thus withdrawn the projecting machine may be operated independently of the driving mechanism so far described, the projecting machine having a motor of its own for normally operating the pictures.

30 It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

40 1. Means operably connected to a talking machine and a picture projecting machine to drive them in synchronism comprising a motor, a motor shaft, a worm on said shaft, a flexible connection in said shaft, a record table, a shaft supporting said table, a worm gear on said shaft, and means for adjusting the said worm toward the said worm gear for taking up lost motion between the shaft of the motor and the shaft of the record table, 45 substantially as set forth.

50 2. Means operably connected to a talking machine and a picture projecting machine for driving them in synchronism comprising a motor, a motor shaft, a record table, 55 a shaft supporting said table, a flexible connection in said shaft between the motor and the record supporting table, a worm on said motor shaft and a gear on the record table supporting shaft, a bearing supporting one end of the motor shaft, and means for adjusting the said bearing to adjust the motor shaft with respect to the record table supporting shaft, and means in said flexible connection for providing axial movement for the

flexible connecting means with the motor shaft, substantially as set forth.

3. Driving means for synchronizing a talking machine record table and picture projecting mechanism comprising a motor, driving connection between the motor and the record table of the talking machine, driving connection between the motor and the picture projecting mechanism including a driving and a driven sprocket and a sprocket chain, 70 the said last named driving connection having a reduction gearing therein, and a shaft removably connected to the driving mechanism, the said removable connection comprising a shaft having a hub at each end, one hub 75 having pins axially positioned therein for engaging between the spokes of a pinion on the picture projecting driving mechanism, and the other hub having a semi-universal joint connection with the sprocket and sprocket 80 chain drive, substantially as set forth.

In witness whereof, I have hereunto set my hand at Waynesboro, Pennsylvania, this twenty seventh day of April, A. D. nineteen hundred and twenty-nine.

WILLIAM R. MOORE, JR.
